CLAIM

The ornamental design for an armoire as shown and described.

DESCRIPTION

FIG. 1 is a perspective view of the armoire;

FIG. 2 is a front elevational view of the armoire;

FIG. 3 is a rear elevational view of the armoire;

FIG. 4 is a left side elevational view of the armoire;

FIG. 5 is a right side elevational view of the armoire;

FIG. 6 is a top plan view of the armoire; and,

FIG. 7 is a bottom plan view of the armoire.

The broken line portions of the drawings are included to show portions of the article that form no part of the claimed design and represent environmental structure only.

1 Claim, 6 Drawing Sheets
